[57] CLAIM

The ornamental design for an aerosol applicator, as shown and described.

DESCRIPTION

FIG. 1 is a front perspective view as viewed from below, of an aerosol applicator showing our new design. FIG. 2 is a view thereof similar to FIG. 1, showing the aerosol applicator in the open position; FIG. 3 is a top plan view thereof;

FIG. 4 is a front elevational view thereof;

FIG. 5 is a right side view, the left side view being a mirror image thereof;

FIG. 6 is a rear elevational view thereof; and

FIG. 7 is a bottom plan view thereof.
